UNITED STATES PATENT OFFICE

JOHN FRANKLIN WHITMAN, JR., OF NEW YORK, N. Y., ASSIGNOR TO EDITH G. STRAUS,
DOING BUSINESS AS MODERN METAL FURNITURE COMPANY, OF NEW YORK, N. Y.

DESIGN FOR A CHAIR FRAME

Application filed March 5, 1930. Serial No. 34,741. Term of patent 7 years.

To all whom it may concern:

Be it known that I, JOHN FRANKLIN WHITMAN, Jr., a citizen of the United States, residing in New York city, in the county of New York and State of New York, have invented a new, original, and ornamental Design for a Chair Frame, of which the following is a specification, reference being had to the accompanying drawing, forming a part thereof.

Figure 1 is a front view of a chair frame showing my new design.

Fig. 2 is a side view thereof.

Fig. 3 is a plan view thereof.

Fig. 4 is a perspective view thereof.

I claim:

The ornamental design for a chair frame, as shown.

In testimony whereof I affix my signature.

J. FRANKLIN WHITMAN, JR.
